(57) **CLAIM**

The ornamental design for a float anchor as shown and described.

DESCRIPTION

FIG. 1 is a front view of a float anchor showing my new design;

FIG. 2 is a rear view of the float anchor;

FIG. 3 is a right side view of the float anchor;

FIG. 4 is a left side view of the float anchor;

FIG. 5 is a top view of the float anchor;

FIG. 6 is a bottom view of the float anchor;

FIG. 7 is a top front side perspective view of the float anchor;

FIG. 8 is a cross-sectional view of the float anchor taken along line 8-8 in FIG. 5; and,

FIG. 9 is a top front side perspective view of the float anchor in use.

The broken lines in FIG. 5 depict cross-sectional cut indicators and form no part of the claimed design. The broken lines in FIG. 9 are illustrative of environmental structure forming no part of the claimed design.
